UNITED STATES PATENT OFFICE.

HARRY U. KISTNER, OF BORDENTOWN, NEW JERSEY.

SNAP-HOOK.

SPECIFICATION forming part of Letters Patent No. 371,690, dated October 18, 1887.

Application filed April 6, 1887. Serial No. 233,859. (No model.)

To all whom it may concern:

Be it known that I, HARRY U. KISTNER, a citizen of the United States, residing at Bordentown, in the county of Burlington, State of New Jersey, have invented a new and useful Improvement in Harness Snaps or Snap-Hooks, which improvement is fully set forth in the following specification and accompanying drawings, in which—

10 Figure 1 represents a side elevation of a snap-hook embodying my invention. Fig. 2 represents a partial side elevation and partial section thereof. Fig. 3 represents an elevation at a right angle to Fig. 1, the closing jaw 15 of the hook being removed. Fig. 4 represents a section in line x x , Fig. 2. Fig. 5 represents a perspective view of another form of snap-hook embodying my invention.

Similar letters of reference indicate corresponding parts in the several figures.

My invention consists in a snap-hook having its shank formed with a recess for a spring and its movable jaw provided with a thumb-piece, the lower portion of which is adapted 25 to enter said recess when the said jaw is depressed.

It also consists in providing the said shank with throats leading from said recess and the movable jaw with necks adapted to enter said 30 throats, as hereinafter set forth and claimed.

Referring to the drawings, A represents the shank or body of a snap-hook; B, the movable jaw, pivoted at a ; C, the hook portion or stationary jaw, and D the loop thereof, said 35 parts in general respects being of usual construction.

The shank A has a round or cylindrical chamber, E, for the reception of the coiled spring F, which bears against the inner or under side of the jaw B, for closing said jaw and holding it in closed position, it being noticed that the outer side of the jaw has a thumb-piece, G, whereby the jaw may be readily

opened, it being also noticed that said piece is of cylindrical form and adapted to enter the chamber E when the jaw is depressed.

The portions of the jaw on opposite sides of the thumb-piece G are reduced, forming necks H H, and the shank A has throats J J on opposite sides of the chamber E to receive 50 said necks H when the jaw is depressed, it being noticed that said throats are in communication with the chamber and are of less width than the diameter thereof.

It will now be seen that the spring F occupies 55 the chamber E and cannot enter the throats J, and is furthermore confined by the jaw B and base of the chamber E, whereby said spring is retained in position by the jaw B and shank A without the necessity of special fastenings.

I am aware that it is common to provide the shank of a snap-hook with a recess adapted to contain the spring which closes the movable jaw; but I am not aware that the movable jaw 65 has been constructed, except as herein claimed, with a thumb-piece having its lower end adapted to enter the spring-recess, as herein shown and illustrated.

Having thus described my invention, what I 70 claim as new, and desire to secure by Letters Patent, is—

A snap-hook consisting of the shank A, with hook portion C, and the cylindrical chamber E, having the throats J J on opposite sides 75 thereof, the movable jaw B, pivoted at a to the shank A and having a thumb-piece, G, thereon, and necks H H on the sides of said thumb-piece, and the coil-spring F on the under side of said movable jaw B and in said 80 chamber E, substantially as described.

HARRY U. KISTNER.
